UNITED STATES PATENT OFFICE

2,150,803

HEAT EXCHANGE UNIT

Clarence A. Leidig, Buffalo, N. Y., assignor of forty-five per cent to Silas C. Wead, North Tonawanda, N. Y.

Application May 6, 1936, Serial No. 78,223

8 Claims. (Cl. 122—20)

This invention relates to a new and improved heat exchange unit and particularly to a device for elevating the temperature of liquids by means of hot gases.

It has heretofore been proposed to utilize the hot gases which are discharged from the fire box of a furnace or similar heating device and transferred to a chimney or smoke stack by means of a conduit or flue. The present invention relates generally to such a device and involves a new and improved heat exchange unit which is mounted or positioned directly in the flue or stack leading from the fire box of a furnace or similar device.

It is an object of the invention to provide a device of this class wherein a high degree of thermal efficiency is obtained with a minimum of interference with the normal flow of spent gases in the discharge conduit leading from the furnace.

In constructing the device of the present invention I have so arranged the various parts that a device very simple in construction, yet rugged and efficient in operation, has resulted.

In the drawings, Fig. 1 is a general view of my invention showing a portion of a furnace and the flue leading therefrom in cross section and my improved heat exchange unit position in the flue and shown in side elevation.

Fig. 2 is a horizontal cross sectional view taken approximately on the line 2—2 of Fig. 3.

Fig. 3 is a vertical cross sectional view taken approximately on line 3—3 of Fig. 2.

Fig. 4 is a fragmentary cross sectional view taken on the line 4—4 of Fig. 1 and showing the liquid inlet port of the device.

Fig. 5 is a perspective view showing that end of my device at which the hot gases enter and to which I shall hereafter refer as the front end.

Fig. 6 is a detailed plan view of a flue section in partly disassembled relation, showing the manner of engaging the flue section about the water outlet pipe of my device.

Fig. 7 is a general side elevational view of a modified means for incorporating my improved heat exchanger in the hot gas outlet of a furnace.

In the embodiment of the invention disclosed in Figs. 1 through 6 of the drawings, I have indicated, at 10 in Fig. 1, the side wall of a furnace having an outlet 11 leading from the fire box for the discharge of the gaseous products of combustion.

The structure is provided with the usual flue 12 leading to a chimney or smoke stack, but contrary to the usual construction, I have provided a special flue section indicated generally at 13 which provides novel means for positioning and incorporating my improved heat exchange unit in the usual discharge structure of a furnace. My improved heater, in the form herein disclosed, comprises a semi-cylindrical casing member 14 which is formed with both of its ends open and,

in the present instance, with a pair of vertically and longitudinally extending partitions 15 and 16 which divide the interior of the casing 14 into three longitudinally extending chambers 17, 18 and 19. Positioned in the chambers 17, 18 and 19 are longitudinally extending tubular members 20, 21 and 22 respectively. Each tubular member has a cross sectional contour which is similar to the cross sectional contour of the interior of its corresponding chamber but smaller in size, and each of the tubular members 20, 21 and 22 is provided with a plurality of protuberances 23, extending from its outer surfaces. When a tubular member is inserted, endwise, in its respective chamber, its protuberances 23 serve to locate the tubular member substantially in the center of its receiving chamber and thereby provide a space between the walls of the tubular member and the interior of the wall of the chamber, which is substantially uniform throughout.

The front and rear ends of the device are provided with closure or header members 24 and 25 respectively. The outer contour of the header members conforms to the outer contour of the semi-cylindrical casing member and each header member is provided with openings corresponding in size to the openings in each of the tubular members 20, 21 and 22.

Spaced about the semi-cylindrical upper portion of the header members 24 and 25 and the casing 14 are a plurality of lugs 26. Longitudinally extending tie rods 27 engage the lugs 26 at their opposite ends and are each provided with an enlarged head portion 28 at one end and a nut 29 at the other for holding the header members 24 and 25 securely against the end faces of the casing member 14 and the tubular members 20, 21 and 22. It will be seen that the header members 24 and 25 will therefore close off the ends of the previously described spaces provided between the outer walls of the tubular members 20, 21 and 22 and the inner wall of the semi-cylindrical casing member 14.

Communication between these three spaces is provided in the following manner. An opening 30 is formed in the partition member 16 at its upper front corner. A second opening 31 is provided in the partition member 15 at its lower rear corner. A liquid intake pipe 32, leading from a cold water supply line or from the bottom of a hot water storage tank, communicates with the space between the tubular member 22 and the walls of the chamber 19 at a point adjacent the rear end of the device, as shown in Figs. 1 and 2. Fig. 4 shows the intake pipe 32 as having a threaded end portion which engages corresponding threads formed upon the interior of a boss 33 provided at the bottom of the casing member 14. The inner periphery of the pipe 32 may be threaded, as shown in Fig. 4, and provided with a re-

ducing bushing 34 for limiting the entry of liquid into the heat exchanger.

A discharge pipe 35 is secured in a boss 36 provided upon the upper side of the casing 14 and 5 communicates with the space between the member 20 and the interior of the wall of the chamber 17 at a point adjacent the front of the device as will appear from Fig. 1. The discharge pipe may feed into the top of a hot water storage 10 tank or lead directly to wherever a supply of hot water is wanted.

It will now be clear that liquid introduced into the heat exchanger by means of the intake pipe 32 at the rear end of the device will traverse longitudinally the space between the tubular member 22 and the walls of the chamber 19 from right to left as seen in Figs. 1 and 2, and flow through the opening 30 into the space between the tubular member 21 and the walls of the 15 chamber 18. The liquid will then traverse this space in a direction from left to right as seen in Figs. 1 and 2, enter the space between the tubular member 20 and the walls of the chamber 17 through the opening 31, and flow through this 20 space from right to left, as seen in Figs. 1 and 2 and be discharged from the device through the pipe 35.

It will be noted that the interiors of the tubular members 20, 21 and 22 are in open communication with the interior of the flue section 13 in which the device is adapted to be positioned. The front closure member 24 is so formed that all of its parts taper away from the casing member 14 in such manner as to provide substantially 30 funnel-like or stream-line entrances 33, 34 and 35 to the interior of the tubes 20, 21 and 22 respectively. This construction is provided to insure the entrainment of a maximum volume of hot flue gases for passage through the tubular members on their way from the furnace to the chimney or stack. This construction also causes the velocity of the gases to be greater in the tubular members than elsewhere in the flue and this greater velocity assists materially in keeping 35 the surface of the passages free from soot or other material which may tend to separate from the gases and deposit thereupon.

While two vertically disposed partitions, 15, 16 have been shown, it will be apparent that the 40 number may be varied and, if desired, the partitions may extend horizontally across the casing 14, one above the other.

Means have been provided in the header member 24 for rendering the unit effective for elevating the temperature of liquids in the absence 45 of hot gases in the flue section 13, as when the furnace 10 is inactive, or when such hot gases are insufficient. These means comprise a passage 40 which extends through all parts of the header member 24 and is in open communication 50 with a fuel gas inlet pipe 41. Gas jets or ports 42 lead from the passage 40 at spaced intervals about the member 24 and terminate at the surface of the member 24 at points closely adjacent the meeting lines of the member 24 and the casing member 14 and the tubular members 20, 21 and 22. The gas inlet line 41 is, of course, provided with a control valve not shown and when this valve is opened, gas will be discharged 55 from all of the jets 42 in a direction generally toward the interior of the tubes 20, 21 and 22. For the ignition of the gas so discharged, a pilot light 43 is provided, positioned directly above a short tubular member 44, that is provided in the 60 upper part of the flue section 13 at a point just

to the rear of the header member 24. A portion of the gas issuing from the several jets 42 will pass through the tubular member 44 and be ignited by the constantly burning pilot light 43, and then burn back into the interior of the flue section 13 to ignite all of the several jets 42.

This gas burner arrangement serves the further useful purpose of burning or blasting out waste solid products of combustion which tend to accumulate upon the outer walls of the casing 14 and the inner walls of the tubular members 20, 21 and 22.

To facilitate the mounting and positioning of the present device, the flue section 13 is formed by a pair of longitudinally extending sheet metal members 45 and 46, approximately semi-circular in cross section and hinged at their bottom edges as at 47. The upper edges of the members 45 and 46 are adapted to overlap for a substantial distance so that the ultimate diameter of the assembled flue section may be readily adapted to suit varying needs. As is shown in Fig. 6, the upper edges of the sections 45 and 46 are provided with U-shaped notches 48 and 49 respectively, which, when brought together about the outlet pipe 31, embrace the pipe 31 and provide a substantial seal between the interior and exterior of the flue section 13 at this point. The portion 46 of the flue section 13 is provided with an opening 50 for receiving the inlet pipe 32.

In assembling the device, the opening 50 of the flue section 13 is first placed over the pipe 32. The casing 14 and its assembled tubular members and header members are then secured to the upper end of the intake pipe 32 and to the lower end of the outlet pipe 35 and are supported thereby, the arcuate upper surface of the casing member 14 being approximately concentric with the assembled flue section 13 so that the space between the upper portion of the casing 14 and the wall of the flue 13 is substantially uniform throughout. Further, this space is as small in size as is consistent with the passage of a sufficient quantity of the hot flue gas through the space to heat the upper surface of the device to approximately the same degree as its other surfaces. In this way there is a minimum of interference with normal passage of the hot flue gases for a given area of the heat exchange unit and the largest possible uninterrupted area, that is, the space below the bottom wall of the casing member 14, is presented. Disposition of the heat exchanger in the upper part of the flue 13 exposes it to contact with the hottest portion 5 of the flue gases which will naturally be in the upper part of the flue.

When a limited amount of hot gas is issuing from the furnace this gas will naturally traverse the upper portion of the conduit and pass through and immediately about the heat exchanger. As the volume of hot gas increases more of it will pass through the uninterrupted space beneath the heat exchanger and will enjoy a normal uninterrupted flow.

The members 45 and 46 of the flue section 13 are then brought together at their upper edges to the position shown in Fig. 3 with the inner peripheries of their front and rear ends embracing the furnace outlet 11 and the flue 12 respectively, and are secured in this position by a pair of circular clamping rings 47 provided with securing screws or bolts 48. This construction renders the heat exchange unit conveniently accessible for cleaning, adjustment, repair, etc.

The modification shown in Fig. 7 involves no change in the heat exchange unit but provides a modified form of flue section 13' which is of sufficiently greater diameter than the furnace outlet 11 and the flue 12 to compensate for the interference with normal passage of waste gas which is offered by the heat exchange unit. This form of my invention will be particularly useful when the cross sectional area of the furnace outlet and flue, 0 or the "draft" as it is called, is insufficient to permit successful interposition of the heat exchange unit in the manner shown in Fig. 1.

In operation the modification of Fig. 7 is similar to the modification previously illustrated with the added advantage that the hottest portion of the waste gases will be trapped or momentarily deterred in its movement by the upwardly extending recess formed by the enlargement of the flue section 13'. This trapping interferes in no way with passage of gas through the unobstructed lower portion of flue section 13' as the rate of flow increases.

It is to be understood that the detailed description herein and the accompanying drawings are merely exemplary and that the scope of the present invention is not limited in any way except as defined in the appended claims.

What is claimed is:

1. A heat exchange unit comprising a unitary casing member having a plurality of longitudinally extending passages formed therein and in communication with each other, tubular members disposed in said passages and means for spacing the walls of the tubular members from the walls of the passages to provide a fluid conduit therebetween, fluid inlet and outlet ports in communication with said fluid conduit, means at each end of said casing member for closing said fluid conduits, said closure means having openings leading to the interiors of said tubular members and one of said closure members having a series of ports, and a conduit for introducing fluid fuel into said closure member for discharge through said ports.

2. In combination with a furnace having a conduit for carrying off the gaseous products of combustion, a readily detachable flue section interposed in said conduit, means for adjusting the diameter of said flue section to fit said conduit, a heat exchanger having fluid passages therein and intake and outlet pipes communicating therewith and disposed in said flue section.

3. A fluid heater comprising a circular conduit having a substantially horizontal axis for conveying the gaseous products of combustion from a furnace, and a heat exchange unit positioned in the upper portion of said conduit and comprising an elongated outer casing extending longitudinally of said conduit and having an arcuate upper surface concentrically disposed with respect to the curvature of said conduit, said elongated outer casing member having an inlet port in its bottom surface and an outlet port in its arcuate upper surface and longitudinal partition members defining a zig-zag fluid passage in said casing.

4. A fluid heater comprising a circular conduit for conveying the gaseous products of combustion from a furnace and a heat exchange unit positioned in the upper portion of said conduit and having a fluid passage therein and inlet and outlet conduits communicating therewith, said heat exchange unit comprising an elongated outer casing extending longitudinally of said conduit

and having an arcuate upper surface and a substantially flat bottom surface, said arcuate upper surface being disposed concentrically with respect to said circular conduit and spaced inwardly therefrom.

5. A liquid heater comprising a conduit for normally conducting a current of a gas at elevated temperatures, a heat exchanger disposed in said conduit and comprising a body portion having longitudinally extending fluid passages therein, inlet and outlet ports communicating with said fluid passages, closure means at each end of said body portion for said fluid passages, and means on one of said closure members for introducing an auxiliary heating medium, said means being associated with the closure member which is nearest to the entry end with respect to the normal current of gas whereby the heat from the auxiliary means will substantially completely traverse said heat exchanger.

6. In combination, a horizontal conduit for carrying off the gaseous products of combustion from a furnace or the like, a portion of said conduit being substantially circular and of greater cross sectional area than the remainder thereof, and a heat exchange unit disposed in the upper part of said portion of said conduit, said heat exchange unit comprising an elongated outer casing extending longitudinally of said conduit and having an arcuate upper surface and a substantially flat bottom surface, said arcuate upper surface being disposed substantially concentrically with respect to said circular conduit and spaced inwardly therefrom, the uninterrupted cross-sectional area below said heat exchange unit being substantially equal to the cross-sectional area of the remainder of said conduit.

7. In combination with a fluid conduit, a heat exchange unit disposed therein and comprising a casing member having a plurality of passages extending longitudinally with respect to said conduit, tubular members disposed in said passages with their walls spaced therefrom to form fluid chambers extending continuously about said tubular members and said tubular members being in open communication at both their ends with the fluid stream in said conduit, means forming connecting passages between said longitudinally extending passages, said means being disposed between each adjacent pair of longitudinally extending passages and disposed alternately at opposite ends thereof, and fluid inlet means communicating with one of said longitudinally extending passages and fluid outlet means connecting with another of said longitudinally extending passages.

8. A heat exchange unit comprising a casing member having a plurality of longitudinally extending passages, tubular members disposed in said passages and means for spacing the walls of the tubular members from the walls of the passages to provide fluid chambers extending about said tubular passages, said tubular members being removably positioned in said passages, closure means at each end of said casing for closing said fluid chambers and openings in said closure means providing free fluid communication between the interior of the tubular members and the surrounding atmosphere, said tubular members being retained in said passages by said closure members, and said passages being interconnected for fluid communication and having an inlet and an outlet port.
